US00D995544S

(12) **United States Design Patent** (10) **Patent No.:** **US D995,544 S**
(45) **Date of Patent:** **** Aug. 15, 2023**

(54) **DISPLAY PANEL WITH GRAPHICAL USER INTERFACE**

(71) Applicant: **Phonot Co., Ltd.**, Seoul (KR)

(72) Inventor: **Dong Gyun Kang**, Seoul (KR)

(73) Assignee: **Phonot Co., Ltd.**, Seoul (KR)

(**) Term: **15 Years**

(21) Appl. No.: **29/810,820**

(22) Filed: **Oct. 8, 2021**

(30) **Foreign Application Priority Data**

Apr. 12, 2021 (KR) 30-2021-0017432

(51) **LOC (14) Cl.** **14-04**

(52) **U.S. Cl.**

USPC **D14/485**; D14/489

(58) **Field of Classification Search**

USPC D14/489-495, 485-488

CPC .. G06F 3/048; G06F 3/04842; G06F 3/04845;

G06F 3/0481; H04M 1/724-72484

CLAIM

I claim the ornamental design for a display panel with graphical user interface, as shown and described.

DESCRIPTION

The sole FIGURE is a front view of a display panel with graphical user interface showing my new design.

The outermost broken line in the FIGURE depicts a display panel that forms no part of the claimed design.

1 Claim, 1 Drawing Sheet
